[57] **CLAIM**

The ornamental design for a body for a dual compartment bottle, as shown and described.

DESCRIPTION

FIG. 1 is a left side perspective view of our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines showing a dual dispensing nozzle cap and a bottle base are for illustrative purposes only and do not form part of the claimed design.
